UNITED STATES PATENT OFFICE.

ROBERT HUGH COSGROVE, OF SPOKANE, WASHINGTON.

ENTRY-TAG.

No. 874,835.

Specification of Letters Patent Patented Dec. 24, 1907.

Application filed November 27, 1906. Serial No. 345,801.

To all whom it may concern:

Be it known that I, ROBERT HUGH COSGROVE, a citizen of the United States, and a resident of Spokane, in the county of Spokane and State of Washington, have invented 5 a new and Improved Entry-Tag, of which the following is a full, clear, and exact description:

The purpose of the invention is to provide 10 a tag especially adapted for marking the exhibits at fairs, and similar places of display, and to so construct the tag that a removable gummed or cemented panel constitutes a portion of the tag, the panel being located 15 adjacent to the panel or space for the name, or name and address of the exhibitor, the relation of the two panels being such that the removable panel may be folded and secured in position over the name panel, acting 20 as a flap to conceal the exhibitor's name until after the exhibit has been judged.

The invention consists in the novel construction and combination of the several parts, as will be hereinafter fully set forth 25 and pointed out in the claims.

Reference is to be had to the accompanying drawings forming a part of this specification, in which similar characters of reference indicate corresponding parts in all the figures.

Figure 1 is a front elevation of the improved tag as it appears when about to be attached to an exhibit; Fig. 2 is a similar view 30 of the tag, showing the concealing flap partially removed from the body of the tag; and Fig. 3 is an enlarged vertical section through the tag folded as shown in Fig. 1.

The tag may be made of any desired dimensions and from any appropriate material. It consists practically of a body section 40 A and a detachable concealing flap or panel B, which by preference is at the bottom portion of the body A, being separated therefrom by a line of perforations 10; indentations, or the equivalent thereof. The detachable concealing flap B is provided with a gummed surface 11 on its inner or front face, preferably at its outer longitudinal or bottom edge.

The body A is shown divided into three 45 panels, namely, a main panel 12, a corner panel 13 and a name panel 14; and in one corner of the body A an aperture 15 is usually provided, through which a cord may be passed for attaching the tag to an article.

The corner panel 13 is divided from the main body panel 12 by lines of perforations 16.

I do not confine myself to any specific display matter on the tag, but the panel 12 usually contains the number of the tag, 60 which is duplicated in the corner panel 13, the name of the fair or show, and also usually the following matter is printed on said main body panel 12, "Division", "Class", "Lot", "Entry Number", "Article"; while upon 65 the name panel 14, which is separated from the concealing flap or panel B by the aforesaid line of perforations 10, a line 17 is usually printed, headed "Exhibiter" and followed by a second line 18, headed "Address". The concealing flap or panel B is of sufficient width when folded over upon the main panel A to cover and completely conceal the name and address of the exhibitor; and at said time the concealing panel is 70 held folded upon the main panel by the cement or gum employed. The corner panel 13 may be dispensed with. When used, however, it is torn off from the tag and retained by the exhibitor until the goods are 75 to be removed when the detached stub or panel is presented for identification.

In Fig. 1 I have illustrated the tag with the concealing flap folded upon the body and secured thereto, completely concealing 80 the name panel 14. In Fig. 2 I have illustrated the concealing flap as separated at its gummed portion from the main panel and also partially torn therefrom.

When a tag of the character described is 85 employed the names of the exhibitors are kept concealed until the judges have passed upon the articles.

Having thus described my invention, I claim as new, and desire to secure by Letters 90 Patent,—

1. An entry tag for fairs and other places of display exhibitions, provided with a main panel at one end having a corner panel separated from the main panel by a weakened 100 line, a concealing panel at the other end of the tag, and a name panel between the main and the concealing panel, the said concealing panel being separated from the name panel by a weakened line and arranged to be 105 folded over the name panel and secured thereto to conceal the entries thereon.

2. An entry tag for use at fairs and other display exhibitions, sub-divided into a main entry panel at the top of the tag, having a 110

detachable corner panel, a name panel, and a concealing panel at the bottom of the tag and forming a portion of the tag proper, being partially separated from the body panel by a line of perforations located below the name panel, the said concealing panel being adapted to be folded over upon the name panel to conceal the same, and a cementing material carried by the concealing panel on its front face at its bottom edge.

3. An entry tag provided with a main entry panel at one end thereof having a corner panel divided from the body of the main

panel by a line of perforations, an intermediate panel, and a detachable concealing panel at the other end of the tag, and adapted to be folded over the intermediate panel and secured in said folded position.

In testimony whereof I have signed my name to this specification in the presence of two subscribing witnesses.

ROBERT HUGH COSGROVE.
